ABSTRACT OF THE DISCLOSURE

A process for preparing water-insoluble azo dyestuffs on textile material of cellulose or protein fibers comprising treating the textile material in an alkaline bath which contains a coupling component, a diazoamino compound of the formula

wherein R represents phenyl, halogenophenyl, alkylphenyl, alkoxyphenyl, dialkylphenyl, alkylhalogenophenyl, alkoxyhalogenophenyl, alkylcarbamylphenyl, alkoxycarbamylphenyl, alkylsulfamylphenyl, alkoxysulfamylphenyl, alkyl(alkyl- or aralkyl-sulfonyl) phenyl, alkoxy(alkyl- or aralkyl-sulfonyl) phenyl or acylaminophenyl, Alk represents lower straight or branched chain alkyl which may be substituted by carboxyl, and R₁ represents carboxyalkyl, sulfoalkyl or sulfophenyl which may be substituted by a halogen atom or alkyl, a wetting or dispersing agent and, optionally, a mineral salt, and then causing formation of the dyestuff by a treatment with acid agents in the same bath at temperatures below 40° C.

The present invention provides a process for the production of water-insoluble azo dyestuffs on textile material of cellulose or protein fibers.

It has been found that water-insoluble azo dyestuffs can be produced on textile material of cellulose or protein fibers by treating the textile material in an alkaline bath which contains a coupling component and a diazoamino compound of the Formula 1

in which R represents phenyl, halogenophenyl, alkylphenyl, alkoxyphenyl, dialkylphenyl, alkylhalogenophenyl, alkoxyhalogenophenyl, alkylcarbamylphenyl, alkoxycarbamylphenyl, alkylsulfamylphenyl, alkoxysulfamylphenyl, alkyl(alkyl- or aralkyl-sulfonyl) phenyl, alkoxy(alkyl- or aralkyl-sulfonyl) phenyl or acylaminophenyl, Alk represents lower straight or branched chain alkyl which may be substituted by carboxyl, and R₁ represents carboxyalkyl, sulfoalkyl or sulfophenyl which may be substituted by a halogen atom or alkyl, furthermore a wetting or dispersing agent and, if desired, a mineral salt, and then causing formation of the dyestuff by a treatment with acid agents at temperatures below 40° C.

The process of the present invention is carried out by treating the textile material in the form of yarn hanks, wound bodies, slubbings or piece goods in an alkaline bath which contains a coupling component having high substantivity and a diazo-amino compound of the indicated composition as well as a wetting or dispersing

agent and, if desired, a mineral salt, for example, sodium chloride, sodium phosphate or sodium sulfate. The treatment is carried out for at least 10 minutes in order to ensure that the coupling component is sufficiently and uniformly fixed onto the textile material. In general, the process is carried out at temperatures between about 10° and about 35° C., suitably at room temperature or at a slightly elevated temperature. When the coupling component is essentially fixed and has levelled, an organic acid, for example, formic acid, acetic acid, tartaric acid, citric acid, lactic acid or glycollic acid, a mixture of these acids, a mixture of a mineral acid, for example, hydrochloric acid or sulfuric acid, with an organic acid or a mixture of a mineral acid with the salt of an organic acid, is added to the bath in a quantity such that the total quantity of alkali in the bath and on the textile material is neutralized and a pH-value of between about 4 and 7 is reached.

The pH-value required for obtaining optimum dyestuff yield depends, above all, on the diazoamino compound of the Formula 1 used. For example, in the case of compounds in which R is alkoxyhalogenophenyl or alkylhalogenophenyl the pH-value is at about 5, in the case of compounds in which R is alkoxycarbamylphenyl it is at about 5, in the case of compounds in which R is alkoxy-sulfamylphenyl at about 4 and in the case of compounds in which R is acylaminophenyl it is at about 6.

The temperature required for the dyestuff formation is in the range of between about 10° and about 40° C. After the formation of the dyestuff on the textile material has taken place, the material is subsequently washed in a neutral or acid bath, if desired or required in the presence of dispersing agents, and the dyeing is further treated in the usual manner. In this manner, dyeings are obtained which exhibit very good fastness to rubbing.

35 Piece goods can be dyed in the following manner: the goods are impregnated on a two or multiple roller foulard with a mixture of the coupling component and an excess of diazoamino compound, the goods are wound up and after a period of stay of, for example, half an hour, coupling is effected at temperatures below 40° C. by passing the goods through an organic acid, a mixture of organic acids or a mixture of organic and mineral acids. This dyestuff development may be effected by a single passage in a compartment of a roller vat or by several 40 passages in a jigger or winch beck; the addition of mineral salts and dispersing agents during impregnation and development may sometimes have a very advantageous effect. In this method of operation, the concentration of the coupling component in the initial bath must be lower in comparison to that of the second bath, corresponding to the higher affinity of the coupling component, whereas the concentration of the diazoamino compound in the initial bath compared to that of the second bath is not to be reduced. This method of operation saves energy; intermediate drying of the dyestuff prior to the development of the dyestuff is not required.

45 As coupling components, there may be used in the process of the present invention compounds which are distinguished by a high substantivity towards the textile material used, i.e. coupling components, which at a goods to liquor ratio of 1:20, a dyeing period of 30 minutes, at 30° C., a concentration of 1 g. per liter of water, without addition of salt and with an excess of 50 4.5 g. of sodium hydroxide per liter of bath, have so high a substantivity that at least 9 g. are absorbed on 1 kg. of cotton. Suitable compounds are, for example, 2,3-hydroxynaphthoyl-aminobenzenes such as 1-(2',3'-hydroxynaphthoylaminino)-2,5-dimethoxy-4-chlorobenzene or 1-(2',3'-hydroxynaphthoylaminino)-2-methoxy-4-chloro-5-methylbenzene, 6-bromo- or 6-methoxy-2,3-hydroxynaphthoic acid aryl amides such as 1-(6'-bromo-

2',3' - hydroxynaphthoylamino)-2-methoxybenzene, condensation products of 2,3-hydroxynaphthoic acid and oligonuclear isocyclic or heterocyclic amines such as 2-(2',3' - hydroxynaphthoylamino)-naphthalene, 2-(2',3'-hydroxynaphthoylamino) - carbazole, 2 - (2',3'-hydroxynaphthoylamino) 3-methoxy-diphenylene oxide, 6-(2',3'-hydroxynaphthoylamino) - benzimidazole, 6 - (2',3'-hydroxynaphthoylamino) - indazole, 5-(2',3'-hydroxynaphthoylamino)-2-methylbenzthiazole or 4 - (2',3'-hydroxynaphthoylamino)-diphenyl and the substitution products thereof, 4,4' - bis(2',3'' - hydroxynaphthoylamino) - diphenyl and the substitution products thereof such as 4,4'-bis - (2'',3'' - hydroxynaphthoylamino)-3,3'-dimethoxydiphenyl, 1,4-bis-(2'',3''-hydroxynaphthoylamino)-benzene and the substitution products thereof, 4,4'-bis-(2'',3''-hydroxynaphthoylamino)-stilbene, 4,4'-bis-(2'',3'' hydroxynaphthoylamino)-azobenzene and the substitution products thereof, 4,4'-bis-(2',3''-hydroxynaphthoylamino)-diphenyl urea, 2-hydroxyanthracene-3-carboxylic acid aryl amides such as 1-(2'-hydroxyanthracene-3'-carboylamino) - 2 - methylbenzene, 2 - hydroxycarbazole-3-carboxylic acid aryl amides such as 1-(2'-hydroxycarbazole-3' - carboylamino)-4-chlorobenzene, 5-hydroxy-1,2,1',2'-benzocarbazole-4-carboxylic acid aryl amides such as 1-(5' - hydroxy - 1',2',1'',2''-benzocarbazole-4'-carboylamino)-4-methoxybenzene or 1-(5'-hydroxy-1',2',1'',2''-benzocarbazole - 4'-carboylamino)-2-methyl-4-methoxybenzene, or terephthaloyl-bisacetic acid aryl amides such as terephthaloyl - bis - (1-acetylaminocarboxylic acid-2-methoxy-4-chloro-5-methylbenzene) - or terephthaloyl-bis-(1-acetylaminocarboxylic acid-2-methoxy-4-chloro-5-methylbenzene).

As diazoamino compounds, there may especially be used compounds obtained by coupling diazotized aniline, diazotized chloroanilines, toluidines, anisidines, xylidines, chlorotoluidines, chloroanisidines or diazotized aminoalkoxybenzoic acid amides, aminoalkoxybenzenesulfonic acid amides, aminoalkylbenzenesulfonic acid amides or aminoalkylbenzoic acid amides which may be substituted in the amide group by alkyl or aryl radicals, diazotized aminoalkylphenyl (alkyl or aralkyl)-sulfones, aminoalkoxyphenyl (alkyl- or aralkyl)-sulfones or monoacylated phenylene-diamines, with the alkali metal salts or alkaline earth metal salts of N-alkylated aliphatic α , β - or γ -amino-carboxylic acids, for example, N-(methyl)-aminoacetic acid, N-(butyl)- β -aminopropionic acid, N-propyl- β -aminobutyric acid or N-(methyl)- α -aminopropionic acid, of N-alkyltaurines, especially of N-methyltaurine, of imidodiacetic acid, of an iminodipropionic acid or iminodibutyric acid, or of N-alkysulfanilic acids which may be substituted by a halogen atom or by an alkyl group.

As wetting or dispersing agents, there may be used the compounds conventionally used in ice colour technique, for example, condensation products of higher molecular fatty acids and protein degradation products, condensation products of higher molecular fatty acids and aminoalkysulfonic acids, condensation products of formaldehyde with naphthalene-sulfonic acids, or purified sulfite cellulose waste liquor.

The process can be applied to textile material of natural or regenerated cellulose, cyanoethylated cellulose, wool, natural silk or regenerated protein fibers.

Compared with the usual dyeing methods with ice colours, the process of the present invention is considerably simpler. In the known dyeing methods, the dye-bath is usually drained after the impregnation with the coupling component, the goods are centrifuged, separated with suction or rinsed intermediately and the dyestuff is developed with a diazonium compound in a second bath. In contradistinction thereto, in the process of the present invention impregnation and development are carried out in one bath and after the period of stay required for fixing the coupling component, coupling is effected without any other intercalated operation, which saves operational time to a considerable degree.

It is generally known that diazoamino compounds of diazotized aromatic amines and N-(methyl)-aminoacetic acid, imidodiacetic acid, N-methyltaurine or N-alkylsulfanilic acids may be used for the production of azo dyestuffs on the fiber, by printing such diazoamino compounds in admixture with coupling components on the material and developing the dyestuffs by a treatment with acids. This process is at present widely used in industry. However, it has not been known as yet and, in view of the state of the art, it was very surprising that such mixtures can also be used for the dyeing of fibers in any processing stages, even of wound bodies, without intermediate drying of the goods.

It is known that water-insoluble azo dyestuffs can be produced on vegetable fibers by treating these fibers at long goods to liquor ratios with a bath containing a coupling component and a diazo or tetrazoamino compound without hydrosolubilizing groups and subsequently developing the azo dyestuff by treatment with an acid bath (German Patent 1,057,061).

In comparison with this process, the process of the present invention, which is carried out with substantive coupling components and diazoamino compounds of the indicated Formula 1 is distinguished by the fact that the development of the dyestuffs can be effected at low temperatures and that it is not necessary to raise the temperature after the addition of acid. Another advantage of the process of the present invention is that the diazoamino compound with aliphatic aminocarboxylic acids as stabilizers are present in the bath in the form of dissolved alkali metal salts, which ensures complete penetration of the material to be dyed and thus complete coupling, whereas, if water-insoluble diazoamino compounds are used, these compounds are only deposited on the surface of the material to be dyed which turns out in unsatisfactory dyeings and fastness to rubbing.

The following examples illustrate the invention, but they are not intended to limit it thereto:

EXAMPLE 1

A cross-wound bobbin of 500 g. of cotton was treated for 30 minutes at 30° C. on a dyeing apparatus in the following bath:

7 g. of 2-(2',3'-hydroxynaphthoylamino)-naphthalene were dissolved in 14 cc. of denatured ethyl alcohol, 7 cc. of water having 60° C., 2.8 cc. of a 38° Bé. sodium hydroxide solution and 3.5 cc. of a 33% formaldehyde solution, and introduced into a bath containing 5 g. of a condensation product obtained from an aminoalkylsulfonic acid and a higher molecular fatty acid, 30 cc. of a 38° Bé. sodium hydroxide solution, 42 g. of trisodium phosphate, 25 g. of sodium chloride and 16.3 g. of the diazoamino compound of diazotized 1-amino-2-methoxy-4-benzoylamino-5-methylbenzene and the sodium salt of N-(methyl)-aminoacetic acid in 5 liters of water having 30° C. 75. cc. of a 50% acetic acid were added and the treatment was carried on for 30 minutes. The bobbin was then rinsed hot and cold and treated for 15 minutes, at 60° C., with 12.5 g. of a mixture of 63% of perchloroethylene, 17% of a reaction product of about 10 mols of ethylene oxide and 1 mol of nonyl phenol and 20% of isopropyl alcohol and 2.5 g. of the sodium salt of nitrilotriacetic acid in 5 liters of water, was then rinsed, soaped for 15 minutes at boiling temperature with 5 g. of a condensation product of an aminoalkylsulfonic acid and a higher molecular fatty acid and 2.5 g. of the sodium salt of nitrilotriacetic acid in 5 liters of water, rinsed and dried. A red violet dyeing having very good properties of fastness was obtained.

EXAMPLE 2

Cotton yarn was treated, at a goods to liquor ratio of 1:20, for 30 minutes, at 30° C., in the following bath:

3 g. of 1-(2',3'-hydroxynaphthoylamino)-2-methoxy-4-chloro-5-methylbenzene were dissolved in 6 cc. of de-

natured ethyl alcohol, 1.5 cc. of a 38° Bé. sodium hydroxide solution, 3 cc. of water having 70° C. and 3 cc. of a 33% formaldehyde solution, and introduced into a solution of 1 g. of a condensation product of an aminoalkylsulfonic acid and a higher molecular fatty acid, 4.75 g. of the diazoamino compound of diazotized 1-amino-2-

methyl-4-chlorobenzene and the sodium salt of N-(butyl)- β -aminopropionic acid, 5 cc. of a 38° Bé. sodium hydroxide solution in 1 liter of water having 30° C. Then, 10.2 cc. of a 50% acetic acid were added and the cotton yarn was treated for 30 minutes at pH 5 to 5.5. The yarn was then rinsed, soaped at 60° and 95° C. under weakly

alkaline conditions, rinsed and dried. A red dyeing having good fastness to rubbing was obtained.

The following table indicates a number of other components which may be used in accordance with the present invention and the tints of the azo dyestuff produced on cellulose fibers.

EXAMPLE 3

A cross-wound bobbin of 500 g. of cotton yarn was wetted for about 15 minutes, at 40-50° C., with a highly effective wetting agent and the wetting liquor was discharged. The bobbin was then treated for 30 minutes, at 30° C. on a dyeing apparatus with a solution containing, in 6 liters of water, 48 cc. of a sodium hydroxide solution of 38° Bé., 120 g. of sodium chloride, 6 g. of a condensation product of oleic acid chloride and methyltaurine, 13.7 g. of the diazoaminio compound of diazoaminized 1-amino-2-methyl-3-chlorobenzene and methyltaurine sodium, and 9.6 g. of 2-(2',3'-hydroxynaphthoyl-amino)-naphthalene which had been dissolved in 19.2 cc. of denatured ethyl alcohol, 3.84 cc. of a sodium hydroxide solution of 38° Bé., 9.6 cc. of water having 60° C. and 9.6 cc. of 30% formaldehyde solution. Then, with circulating bath, 86 cc. of 50% acetic acid were slowly

added and the liquor was circulated again for half an hour. The bath was then drained, the bobbin was rinsed with water and neutralized with a 30-40° C. warm solution of 3 g. of a condensation product of oleic chloride and methyltaurine and 12 g. of sodium carbonate, in 6 liters of water, then rinsed and treated, each time for 15 minutes at 60° C. and at the boiling temperature with a non-ionic detergent with addition of the sodium salt nitrilotriacetic acid, rinsed hot and cold and dried. A vivid scarlet dyeing was obtained.

EXAMPLE 4

1 kg. of wetted cotton yarn was treated for 30 minutes, at 20-25° C., in a bath containing, in 20 liters of liquor, 80 cc. of a sodium hydroxide solution of 38° Bé., 340 g. of trisodium phosphate, 20 g. of a condensation product of oleic acid chloride and methyltaurine, 45.6 g. of the diazoaminio compound of diazotized 1-amino-2,5-di-

ethoxy-4-benzoylaminobenzene and methyltaurine sodium, 280 g. of sodium chloride, and 20 g. of 1-(2',3'-hydroxy-naphthoyl-amino)-4-chlorobenzene which had been dissolved in 40 cc. of denatured ethyl alcohol, 10 cc. of a sodium hydroxide solution of 38° Bé., 20 cc. of water, and 20 cc. of a 30% formaldehyde solution. Then, 265 cc. of 50% acetic acid were added portionwise and the yarn was further treated for half an hour at pH 6.5-6. The yarn was rinsed, neutralized with a sodium carbonate solution and soaped, each time for 15 minutes, at 60° C. and at 95° C., with a non-ionic detergent with the addition of 0.5 g. of the sodium salt of nitrilotriacetic acid per liter of bath, rinsed and dried. A vivid navy blue dyeing was obtained.

The following table indicates a number of other components which may be used according to the present invention and the tints of the azo-dyestuffs produced on cellulose fibers.

Diazoamino compound of methyltaurine-sodium and diazotized	Coupling component	Tint
1-amino-2-chlorobenzene	2-(2',3'-hydroxynaphthoyl-amino)-3-methoxy-diphenylene oxide.	Red brown.
1-amino-2-chloro-4-benzoyl-amino-5-methoxy-benzene	1-(2',3'-hydroxynaphthoyl-amino)-2,5-dimethoxy-4-chlorobenzene.	Dark violet.
1-amino-2,5-dimethoxy-4-benzoylaminobenzene	2-(2',3'-hydroxynaphthoyl-amino)-3-methoxy-diphenylene oxide.	Dark blue.
1-amino-2,4-dimethoxy-5-benzoylaminobenzene	do	Dark violet.
1-amino-2-methyl-4-chlorobenzene	1-(2',3'-hydroxynaphthoyl-amino)-2-methoxy-4-chloro-5-methylbenzene.	Red.
1-amino-2-methyl-5-chlorobenzene	do	Red.
1-amino-2-methoxybenzene-5-carboxylic acid amide	1-(2',3'-hydroxynaphthoyl-amino)-2,5-dimethoxy-4-chlorobenzene.	Red.
1-amino-2-methoxy-5-chlorobenzene	2-(2',3'-hydroxynaphthoyl-amino)-naphthalene	Bordeaux.
1-amino-2,4-dimethyl-5-benzoylaminobenzene	do	Red.
1-amino-2-methoxy-4-benzoylaminobenzene	2-(2',3'-hydroxynaphthoyl-amino)-3-methoxy-diphenylene oxide.	Brownish Bordeaux.
1-amino-2-methoxy-benzene-5-sulfonic acid diethylamide	2-(2',3'-hydroxynaphthoyl-amino)-naphthalene	Red.
1-amino-2-methoxybenzene-5-sulfonic acid dimethyl amide	2-(2',3'-hydroxynaphthoyl-amino)-2,5-dimethoxy-4-chlorobenzene.	Yellowish red.
1-amino-2-methoxy-benzene-5-carboxylic acid phenyl amide	1-(2',3'-hydroxynaphthoyl-amino)-2,5-dimethoxy-4-chlorobenzene.	Do.
1-amino-2-methoxy-5-benzylsulfonylbenzene	2-(2',3'-hydroxynaphthoyl-amino)-3-methoxydiphenylene oxide.	Red.
1-amino-2-methyl-3-chlorobenzene	1-(2',3'-hydroxycarbazole-3'-carboxylamino)-4-chlorobenzene	Red brown.
1-aminobenzene	2-(2',3'-hydroxynaphthoyl-amino)-naphthalene	Scarlet.
1-amino-2-methylbenzene	do	Do.
1-amino-2-methoxybenzene	do	Bordeaux.

EXAMPLE 5

Cotton on cross-wound bobbins was treated, at a goods to liquor ratio of 1:10, for half an hour, at 25-30° C., in a bath containing, per liter of liquor, 1 g. of the sodium salt of ethylenediaminetetraacetic acid, 1 g. of a condensation product of oleic acid and methyltaurine, 6.4 cc. of a sodium hydroxide solution of 38° Bé., 1.1 g. of 2-(2',3'-hydroxynaphthoyl-amino)-naphthalene, 30 g. of sodium chloride and 2.25 g. of the diazoamino compound of the formula

After half an hour, 11.5 cc. of 50% acetic acid per liter of bath were added and the yarn was further treated for half an hour. The yarn was then rinsed and soaped each time for 15 minutes at 60° C. and at the boiling temperature, with a solution containing per liter of water, 1 g. of a condensation product of oleic acid and methyltaurine and 0.5 g. of the sodium salt of nitrilotriacetic acid, rinsed and dried. A red dyeing was obtained which was fast to rubbing.

EXAMPLE 6

The process was carried out as described in Example 1, but using 2.4 g. of the diazoamino compound of the formula

A red dyeing was obtained which was fast to rubbing.

EXAMPLE 7

A knitted fabric of cotton was treated, at a goods to liquor ratio of 1:20 for 30 minutes, at 30° C., in a bath containing, per liter of liquor, 1 g. of the sodium salt of ethylenediaminetetraacetic acid, 1 g. of a condensation product of oleic acid and methyltaurine, 6.5 cc. of a sodium hydroxide solution of 38° Bé., 1 g. of 2-(2',3'-hydroxynaphthoyl-amino)-3-methoxydiphenylene oxide,

20 g. of sodium chloride and 2.35 g. of the diazoamino compound of the formula

After half an hour, 11 cc. of 50% acetic acid were added per liter of bath and the fabric was further treated for about 30 minutes. The fabric was then rinsed and soaped as indicated in Example 1. A Bordeaux dyeing was obtained which was fast to rubbing.

EXAMPLE 8

The process was carried out as described in Example 3, but using 1.85 g. of the diazoamino compound of the formula

A red dyeing was obtained which was fast to rubbing.

EXAMPLE 9

Cotton yarn was treated at a goods to liquor ratio of 1:20, at 25-30° C., in a bath containing, per liter of liquor, 1 g. of the sodium salt of ethylenediaminetetraacetic acid, 1 g. of a condensation product of oleic acid and methyltaurine, 7.5 cc. of a sodium hydroxide solution of 38° Bé., 1 g. of 2-(2',3'-hydroxynaphthoyl-amino)-3-methoxydiphenylene oxide, 20 g. of sodium chloride, and 2.15 g. of the diazoamino compound of the formula

60

65

70

After half an hour, a mixture of 6.35 cc. of hydrochloric acid of 20° Bé. and 6 cc. of 50% acetic acid was added, per liter of bath, and dyeing was continued for about half an hour. The yarn was then rinsed, soaped each time for 15 minutes, at 60° C. and at 95° C., with a solution containing, per liter of water, 1 g. of condensation product of oleic acid and methyltaurine, 0.5 g. of the sodium salt of

13

nitrilotriacetic acid and 0.5 g. of sodium carbonate, rinsed and dried. A red dyeing was obtained which was fast to rubbing.

EXAMPLE 10

Cotton yarn was treated, at a goods to liquor ratio of 1:20, for 15 minutes at 30° C., in the following bath: 1 g. of 2 - (2',3'-hydroxynaphthoylamino) - 3 - methoxy-diphenylene oxide was dissolved in 2 cc. of denatured ethyl alcohol, 0.5 cc. of sodium hydroxide solution of 38° Bé., and 2 cc. of water having 70° C., and introduced into a bath containing 2.17 g. of a 30% diazoamino compound of diazotized 1-amino-2-methyl-5-chlorobenzene and the sodium salt of N-methylsulfanilic acid, 1 g. of a condensation product of oleic acid and methyltaurine and 7 cc. of sodium hydroxide solution of 38° Bé. The bath was then made up to 1 liter by means of water. 20 g. of sodium chloride were then added, and the yarn was further treated for 15 minutes, 10.6 cc. of 50% acetic acid were added and the treatment was continued for 30 minutes. The yarn was then rinsed, soaped each time for 15 minutes at 60° C. and at 95° C. with a solution containing, per liter of water, 1 g. of condensation product of oleic acid and methyltaurine and 0.5 g. of the sodium salt of nitrilo-triacetic acid, rinsed and dried. A red dyeing having very good properties of fastness was obtained. When, in the above example, 4.02 g. of a 16.4% diazoamino compound of diazotized 1-amino - 2 - methyl-5-chlorobenzene and the sodium salt of N-ethyl-sulfanilic acid, or 4.75 g. of a 16.3% diazoamino compound of diazotized 1-amino - 2 - methoxybenzene-5-carboxylic acid amide and the sodium salt of N-ethyl-sulfanilic acid were used instead of the diazoamino compound of diazotized 1-amino-2-methyl-5-chlorobenzene and the sodium salt of N-methyl-sulfanilic acid, red dyeings having very good properties of fastness were obtained.

When, in the above example, 0.74 g. of 2-(2',3'-hydroxynaphthoylamino)-naphthalene and 30 g. of sodium chloride, were used instead of 1 g. of 2-(2',3'-hydroxynaphthoylamino) - 3 - methoxy-diphenylene oxide, a yellowish red dyeing having good properties of fastness was obtained.

Diazoamino compound of the sodium salt of N-ethylsulfanilic acid and diazotized	Coupling component	Tint
1-amino-2-methoxybenzene-5-carboxylic acid amide	1-(2',3'-hydroxynaphthoylamino)-2,5-dimethoxy-4-chlorobenzene	Vivid red.
1-amino-2-methyl-3-chlorobenzene	2-(2',3'-hydroxynaphthoylamino)-naphthalene	Scarlet.
1-amino-2-methoxybenzene-5-sulfonic acid diethyl amide	do	Red.
1-amino-2-methyl-3-chlorobenzene	1-(2'-hydroxycarbazole-3'-carboylamino)-4-chlorobenzene	Brown.
Do	1-(5'-hydroxy-1',2',1'',2''-benzocarbazole-4'-carboylamino)-4-methoxybenzene	Bluish red.

The above table indicates a number of other components which may be used according to the present invention and the tints of the azo dyestuffs produced on cellulose fibers.

We claim:

1. A process for producing water-insoluble azo dyestuffs on cellulose and protein textile materials which comprises treating said textile materials at temperatures between about 10° C. and about 35° C. in an aqueous alkaline bath which contains (1) a coupling component which is highly substantive for the textile material employed, said component being selected from the group consisting of arylamides of aromatic ortho-hydroxy carboxylic acids, arylamides of heterocyclic ortho-hydroxy carboxylic acids, arylamides of acyl acetic acids and aryl-

14

amides of terephthaloyl-bis-acetic acid, (2) a diazoamino compound having the formula:

in which R is a member selected from the group consisting of phenyl, chlorophenyl, lower alkylphenyl, lower alkoxy phenyl, di-lower alkylphenyl, lower alkylchlorophenyl, lower alkoxy chlorophenyl, lower alkoxy carbamylphenyl, lower alkoxy-N-(phenyl)-carbamylphenyl, lower alkyl-N,N-(di-lower alkyl)-sulfamylphenyl, lower alkoxy-chloro-benzoylaminophenyl, lower alkoxy-benzyl-sulfonylphenyl and lower alkoxy-lower alkylsulfonylphenyl, Z represents a member selected from the group consisting of lower alkyl and lower alkylene-COO (alkali metal), and R₁ is a member selected from the group consisting of lower alkylene-COO (alkali metal), lower alkylene-SO₃ (alkali metal) and

20

(alkali metal), and (3) a dispersing agent, and subsequently, without an intermediate drying step, treating said textile materials in the same bath at temperatures of between about 10° C. and about 40° C. with an acid agent selected from the group consisting of organic acids, inorganic acids and mixtures thereof in such an amount that in the bath and on the textile material a pH value between about 4 and 7 is achieved.

2. The process as claimed in claim 1, wherein a coupling component selected from the group consisting of 2-(2',3'-hydroxynaphthoylamino)-naphthalene, 1 - (2',3'-hydroxynaphthoylamino)-2-methoxy - 4 - chloro-5-methylbenzene, 1-(2',3' - hydroxynaphthoylamino)-4-chlorobenzene, 1-(2',3'-hydroxynaphthoylamino)-2,5-dimethoxy-4-chlorobenzene, 2-(2',3' - hydroxynaphthoylamino)-3-methoxy-diphenylene oxide, 1-(2'-hydroxycarbazole-3'-carboylamino)-4-chlorobenzene, 1 - (5'-hydroxy-1',2',1'',2''-benzocarbazole-4'-carboylamino)-4-methoxybenzene and terephthaloyl - bis - (1-acetylamino-2-methoxy-4-chloro-5-methylbenzene) is employed.
